US0D1087950S

(12) **United States Design Patent** (10) **Patent No.:** **US D1,087,950 S**
Liang (45) **Date of Patent:** **** Aug. 12, 2025**

(54) **CELL PHONE STAND**

- (71) Applicant: **Shenzhen Kangchengtai Industrial Co., Ltd.**, Guangdong (CN)
- (72) Inventor: **Zhaofei Liang**, Guangdong (CN)
- (73) Assignee: **SHENZHEN KANGCHENGTAI INDUSTRIAL CO., LTD.**, Guangdong (CN)
- (**) Term: **15 Years**
- (21) Appl. No.: **29/972,115**
- (22) Filed: **Nov. 7, 2024**

Primary Examiner — George J Ulsh*Assistant Examiner* — Rodolfo Castro, Jr.(74) *Attorney, Agent, or Firm* — CANTOR COLBURN LLP(57) **CLAIM**

The ornamental design for a cell phone stand as shown and described.

DESCRIPTION

FIG. 1 is a top, right, front side perspective view of a cell phone stand showing my new design;
 FIG. 2 is a front elevation of the cell phone stand illustrated in FIG. 1;
 FIG. 3 is a rear elevation view of the cell phone stand illustrated in FIG. 1;
 FIG. 4 is a left side elevation view of the cell phone stand illustrated in FIG. 1;
 FIG. 5 is a right side elevation view of the cell phone stand illustrated in FIG. 1;
 FIG. 6 is a top plan view of the cell phone stand illustrated in FIG. 1;
 FIG. 7 is a bottom plan view of the cell phone stand illustrated in FIG. 1; and,
 FIG. 8 is a bottom, left, rear side perspective view of the cell phone stand illustrated in FIG. 1.
